UNITED STATES PATENT OFFICE.

ALBERT L. CROWSON, OF ARCADIA, LOUISIANA.

TEMPORARY BINDER.

1,032,380.

Specification of Letters Patent. Patented July 16, 1912.

Application filed February 20, 1912. Serial No. 678,900.

To all whom it may concern:

Be it known that I, ALBERT L. CROWSON, a citizen of the United States, residing at Arcadia, parish of Bienville, and State of Louisiana, have invented certain new and useful Improvements in Temporary Binders, of which the following is a specification.

This invention relates to temporary binders.

The records of courts, in law and equity causes, accumulate rapidly and have to be kept in such condition that any particular pleading, deposition, or other paper is readily available at any time and the entire record kept in orderly fashion so that the progress of the cause or causes can be followed from time to time, this being particularly true where litigation is pending for long periods as is frequently the case. It is also necessary to keep court records so that the clerk may readily make up an accurate transcript for purposes of appeal. Where an action or cause is pending a long time, the record usually becomes voluminous and the ordinary files or binder, file jackets, etc., prove inadequate, requiring repeated adjustment of the papers and much loss of time and inconvenience as the ordinary files are inadequate because they have only a limited capacity.

My object is to provide a temporary flat file or binder for papers of any character which are added to from time to time, particularly court and attorney records, which will have practically unlimited capacity for expansion so that no matter how voluminous the record becomes, succeeding papers may be added thereto from time to time without disturbing the orderly arrangement of those previously filed and facilitating easy and quick access to all papers.

The invention also contemplates the provision of a flat file or binder by which the pleadings, depositions, exhibits, etc., of an action or cause will be bound together in their order of filing so that the making up of the transcript, if appeal is taken, is facilitated.

50 The invention contemplates the provision of a file or binder having covers which are independent of each other and provided with infolded, reinforced, parts for the adjustment, by fasteners of any desired size, of the papers, in their proper order and by which the order of filing of the papers,

particularly in a live action or cause may be maintained, with adaptation for addition of papers from time to time.

My file or binder is radically distinguished from those heretofore known to the art in that the covers are independent or separate so that their capacity for expansion or separation for the accommodation of additional papers is not limited in any manner, as is the case with those files or binders where the covers are connected together even though such connection be an expandible one. My file or binder is further distinguished from those by the infolding of parts of the cover and the reinforcement thereof in a new manner so that they are adapted to withstand repeated bendings or foldings from use, and I employ fasteners connecting these infolded parts and passing through the papers which are held between them. I preferably employ fasteners of the well known "McGill" type but I do not restrict myself to their use. I may so arrange the fasteners that they are permanently carried by one of the infolded parts of a cover or are separable therefrom.

One embodiment of the invention is set forth fully hereinafter and the novel features of the invention are recited in the appended claims.

In the accompanying drawings:—Figure 1 is a perspective of the present invention, the papers and covers being broken away and one of the covers being turned back to show how the papers are disposed between the covers; Fig. 2, a vertical section, broken away, showing fasteners permanently carried by one of the infolded parts of a cover; Fig. 3, a similar view showing fasteners which are detachable; Fig. 4, a longitudinal section of the file showing the permanently carried fasteners illustrated in Fig. 2; and Fig. 5, a similar view of a part of the file where the fasteners are detachable, as shown in Fig. 3.

The front and rear covers or parts of the file are shown at 1 and 2 and the papers are held by the file, at 3, such papers constituting no part of the file itself but are secured to the infolded parts 1 and 2 by fasteners 4.

The covers 1 and 2 may be of any suitable material, preferably relatively stiff Manila paper of suitable texture and strength to withstand usage to which files are subjected.

The upper ends of parts of the covers 1 and 2 are infolded for their entire width, as shown at 5 and 6. On the outside and inside of the ends of the covers 1 and 2 there are pasted reinforcing strips 7 and 8 which are preferably of some suitably tough but flexible material, such as fabric, buckram, or other material which has the requisite properties to resist fracture or splitting due to the continued use to which a file is subjected and the bending back and forth of the covers. Preferably these reinforcing strips are provided on both the outside and the inside of the covers and the infolded parts 5 and 6 thereof. The covers 1 and 2 are independent of and disconnected from each other so that they may be readily separated or taken apart for insertion of the papers 3 to any desired extent or thickness thereof, or the removal of any or all of said papers which constitute the pleadings, depositions, exhibits, etc., of an action or cause. If the file is used for the maintenance and preservation of court records, suitable fasteners or fastening devices may be employed for connecting the infolded parts 5 and 6 to the papers 3, but I preferably employ fasteners 4 of the well known "McGill" type. Fasteners of this character are adaptable in various sizes and lengths, the largest kind being quite long so that a very large number of the papers 3 can be accommodated and it will be understood that there is no limit to the expansion of the covers 1 and 2, such expansion being limited only by the end of the fastener employed for connecting the infolded parts 5 and 6 to the papers 3. The fasteners 4 may be permanently carried by one of the infolded parts, say that designated by 5, as shown in Fig. 2, by having a part of the reinforcing fabric or strip 8 passed over the head of the fastener which is also clear from Fig. 4. The fasteners 4 may be detachable as shown in Fig. 5, in which event the fabric or other reinforcing strip 8 is not made to cover the heads of the fasteners.

The usefulness of the present invention extends beyond the accumulation of papers

during the progress of a legal proceeding as when the case is concluded, the papers may be filed away in their order, permanently attached together, ready for future reference without liability of any of them becoming detached and misplaced. 55

In offices where a large number of papers accumulate in connection with any particular matter, as with voluminous correspondence, with a certain party, the present binder, being expandible to any desired extent, affords a current binder for all papers in connection with a given subject of correspondence and when finally filed away, constitutes a permanent report of the entire matter. 60

I wish it understood that I do not limit myself to the precise details set forth as various modifications can be resorted to in carrying out the invention without departing from its spirit and scope. 65

Having thus described my invention, what I claim as new and desire to secure by Letters Patent, is:

1. A file or binder having independent and separate covers each provided with an infolded part, flexible reinforcing strips adhesively secured to said infolded parts and to a part of the respective covers where said infolded parts join said cover, and fastening means for connecting the reinforced infolded parts to the papers which are to be held by the file. 75

2. A file or binder having independent and separate covers each provided with an infolded part, flexible reinforcing strips adhesively secured to both faces of said infolded parts and to both faces of a part of the respective covers where said infolded parts join said covers, and fasteners passing through the infolded parts which are adapted to clamp the papers between said infolded parts in a detachable manner. 80 85 90

In testimony whereof, I hereunto affix my signature in presence of two witnesses.

ALBERT L. CROWSON.
